UNITED STATES PATENT OFFICE.

HARRY WILLIAM BROADY, OF NEW YORK, N. Y., AND GUSTAV GEORG HERMAN RYDBERG, OF APPELVIKEN, SWEDEN, ASSIGNEES TO SVENSKA AKTIEBOLAGET LOGG, OF STOCKHOLM, SWEDEN, A CORPORATION OF SWEDEN.

PITOT TUBE.

Application filed April 12, 1926. Serial No. 101,559.

In hydrostatic logs so called Pitot-tubes are used, as well known, which tubes in operative position extend outside the hull and are adapted to transmit the water pressure 5 created by the velocity of the ship to an indicating device, from which the velocity of the ship thus may be read off. Such tubes hitherto generally have been made of brass in order not to be damaged by the corrosive 10 action of the water. Experience, however, has proved that the tubes after some time, longer or shorter, will break off, even if the dimensions of the tube are such, that the tube would be able to withstand the pressure 15 exerted by the water. The breaking off of the tube is explained by the fact that the tube during the running of the ship is uninterruptedly subjected to vibrations, which gradually change the structure of the metal 20 into a crystalline state, which renders the tube brittle. Efforts have been made to prevent the breaking off by strengthening the tube but hitherto no practical means in this respect have been devised.

25 In order to procure a Pitot-tube the character of which is not changed, at least not in an essential degree, the tube is, according to this invention, composed of a strength member, preferably in the shape of a tube of 30 steel or any other suitable material such as Mfonel-metal, and members made of brass or other suitable non-corrosive material, which will protect the said strength member against the corrosive action of the water.

35 The accompanying drawing shows in a longitudinal section a Pitot-tube arranged in accordance with the preferred form of execution of this invention. The drawing shows only the tube, members mounted in 40 the same as well as the casing or frame in which the tube is slidingly mounted and means for fixing the tube in operative and inoperative positions being omitted, as they do not belong to the invention.

45 The Pitot-tube shown in the drawing as an example consists of a tube 1 of steel, which is covered on its inner side with a

tube 2 and on its outer side with a tube 3 both of brass, phosphor-bronze or any other metal which is able to resist the corrosive action of the water. The said tubes or covers 50 2 and 3 will protect the steel tube 1 against the water, so that it does not rust. The brass tubes, evidently, must cover only such parts of the steel tube, as otherwise 55 would come into contact with the water. Owing to the known qualities of steel the tube 1 will well withstand the outer pressure 60 of the water. The vibrations, to which it is subjected, will practically not affect the 65 steel in any essential degree and in any case in a much slighter degree than brass or bronze. At the mounting of the Pitot-tube in the ship, its length must be adapted to the thickness of the bottom of the hull and 70 other conditions, in consequence whereof the cutting off operation generally is effected on board the ship. Together with the tube a mouth-piece 4 of the shown construction is delivered, which, after the tube has been 75 cut to the proper length, is soldered to the same. In special cases the tube may be delivered with the mouth piece fixed to the same. The said brass covers may be applied in any suitable manner for instance 80 by drawing, rolling or soldering.

We claim:

1. A Pitot-tube having a strength member and protective members covering the same, said members being able to resist the 80 corrosive action of the water.
2. A Pitot-tube comprising a tube of steel and inner and outer covers therefor of a metal able to resist the corrosive action of water.
3. A Pitot-tube comprising a tube of steel, an inner tube and an outer tube both of brass and covering the said tube of steel and protecting the same against the corrosive action of water.

85 In testimony whereof we have affixed our signatures.

HARRY WILLIAM BROADY.
GUSTAV GEORG HERMAN RYDBERG.
